PANIC BOLT LATCH AND DOOR
CONSTRUCTION

Daniel C. Hay, Santa Monica, Calif.

Application April 16, 1948, Serial No. 21,535

17 Claims. (Cl. 20—16)

1

This invention relates to door locks and particularly pertains to a panic bolt latch and door construction.

At present it is required by law that public auditoriums, such as schools, churches and theatres, shall be provided with doors which swing outwardly and which may normally be locked to prevent entrance to the auditorium from the outside while responding to instant action to be released when it is desired to open the door from the inside at such times as when fire or other disaster occurs. In many instances doors of this type have been cumbersome in construction and have involved the use of complicated operating mechanism which has been mounted on the outside of the door and the door frame, and which therefore might be easily rendered inoperative. Such structures often require the manipulation of releasing means at the time of an emergency and the attendant confusion and there may be difficulty in unlatching the door. It is the principal object of the present invention, therefore, to provide a panic bolt lock which is simple in construction, certain in operation, and is so designed as to be incorporated completely within the door frame structure, in which the parts may be easily assembled and are not liable to get out of order and will operate effectively at all times.

It is a further object of the present invention to provide a panic bolt lock construction which may be used with any type of door including full glass doors. The structure being so designed as to insure that pressure exerted against the operating bar of the door incident to an effort to open the door will force the operating bar against the latch trigger and cause the door to be instantly unlatched.

The present invention contemplates the provision of a door frame structure within which doors are mounted to swing upon vertical axes, and which frame structure forms a housing for operating mechanism to be actuated automatically to normally hold the door in its latched position and to be instantly released when the door is to be opened from the inside of an auditorium or the like. The said structure also contemplates means for holding the latch mechanism in a disengaged position when the door is open and for positively locking the latch mechanism in an engaged position when the door is closed.

The invention is illustrated by way of example in the accompanying drawings, in which:

Figure 1 is a view in elevation showing a double swinging door of the plate glass type, and which door is mounted within a door frame carrying the panic bolt lock mechanism of which the present invention is concerned.

Fig. 2 is an enlarged view in horizontal section as seen on the line 2—2 of Fig. 1, showing the

2

overhead portion of the lock structure and indicating the position of the door when closed in solid lines and partially open in dotted lines.

Fig. 3 is a view in vertical section through a portion of the door as seen on the line 3—3 of Fig. 2, and indicates the adjustable strike plate and the latch structure associated therewith.

Fig. 4 is a fragmentary view in elevation as seen on the line 4—4 of Fig. 2 and shows the latch structure in its intermediate position.

Fig. 5 is a fragmentary view similar to that shown in Fig. 4 showing the latch structure in its moved position.

Fig. 6 is an enlarged view in vertical section and elevation as seen on the line 6—6 of Fig. 1 and shows the mounting of the operating bar and the mechanism affected thereby.

Fig. 7 is a fragmentary view showing a portion of the latch operating mechanism and the lock in their unlocked position.

Fig. 8 is a fragmentary view similar to Fig. 7 showing the lock mechanism in its locked position.

Fig. 9 is an enlarged fragmentary view of the latch holding and releasing member.

Fig. 10 is a detailed vertical section taken through the door and panic bar at the fitting and pivot pin of the bar.

Referring more particularly to the drawings, 30 10 indicates the door posts of a door frame, at the top of which is a lintel 11. The door posts, as shown in Fig. 2 of the drawings, may be a metal channel structure comprising the web portion 12 and legs 13. The door posts may be spaced apart a distance to accommodate a pair of swinging doors 14, or a single door if desired. A door sill 15 extends across the entrance of the door and between the door posts 10. Suitable bearing structures 16 are mounted in the door sill and carry hinge pins 17 upon which the bottom edges of the doors 14 are pivoted. Complementary pins 18 are disposed at the upper edges of the doors 14 and are in vertical alignment with the pins 17.

It has been explained that the doors may be of any suitable construction. This particular panic bolt lock, however, has special advantages when used in connection with tempered glass doors. Such doors include lower and upper channel members 19 and 20 into which the lower and upper edges of the plate glass elements are fitted and fixed. Mounted upon each of the doors at a suitable height is a panic cross-bar 21. These cross-bars are carried at the free ends of lever arms 22. These arms are secured to fittings 23 by pivot pins 24. The pivot pins 24 are disposed in horizontal alignment, thus allowing the panic bolt cross-bars to have a limited swinging movement around the axis of the pins. Mounted upon the ends of the panic bolt cross-

50 55 bars 21 contiguous to the door posts 10 are

actuating cams 25 for a purpose to be herein-after described.

Referring more particularly to Fig. 3 of the drawings, it will be seen that the upper door channel 20 is formed with a lower channel portion 26 to receive the door glass 27 and an upper enlarged channel 28. The enlarged channel 28 extends across the top of the door. The top of this channel is open and in the channel an adjustable roller strike plate 29 is mounted and carried within the channel. This strike plate may be set and adjusted without any drilling operation since it is formed with a central portion 30 and a pair of opposite end portions 31 which fit between the vertical legs of the channel 28. The end portions 31 are parallel to each other and are spaced apart to accommodate the width of a latch structure 32. On the portions 31 of the strike plate 29 and adjacent to the lower edge of the plate are bosses 33. Threaded bores 34 extend through these bosses and into the plate 29. Cap screws 35 are threaded into the bosses and have a conical outer end face so that the cap screws may be tightened with their heads against one of the vertical legs of the channel 28 while forcing the strike plate toward the opposite vertical leg of the channel 28. Threaded bores 36 are also formed in the portions 31 of the strike plate 29 in a horizontal plane above that of the bores 34. These accommodate screw studs 37 which may be forced against the contiguous leg of the channel 28 and will adjust the strike plate horizontally. Lock nuts 38 are mounted upon the studs 37 to hold them in their set position, and lock nuts 39 are mounted upon the cap screws 35 to hold them in their set position.

A roller 41 is pivotally mounted on a horizontal pin 42 carried at the upper edge of the strike plate 29 and is designed to be engaged by the overhanging latch 40. The latch 40 is mounted upon a pivot pin 44 which is carried in the lintel channel 11' of the door frame by a bearing plate 44'. A spring 40' is wrapped around the pin 44, and one end of this spring engages the latch structure 32 and the other end engages the member 44' and tends to urge the latch member 40 toward its latching position. A rigid extension of the latch forms a pair of spaced arms 45 and 46. The pivot pin 44 is mounted in bearings 47 and 48 of the plate 44' so that the latch structure may oscillate on the pin 44. At the free ends of the arms 45 and 46 are rollers 49 and 50. These rollers rotate upon parallel axes which are at right angles to the axis of the pin 44. Disposed between the rollers 49 and 50 is a cam 51. The cam is formed with opposite arcuate faces 52 and 53 which incline downwardly and inwardly to a point below a pivot shaft 54. The pivot shaft 54 is disposed horizontally upon a suitable bearing 55 and allows the cam 51 to oscillate in a vertical plane. A downwardly extending lever portion 56 is defined by the opposite curved faces 52 and 53. At the free end of the lever 56 is a pivot pin 57 which carries a U-shaped yoke 58. The yoke 58 has a pair of up-turned legs 59 and 60 which are spaced a distance apart agreeing with the spacing of the rollers 49 and 50. The ends of these legs are semicircular and convex. When this yoke is in its intermediate position the legs of the yoke extend vertically and register with the under faces of the rollers 49 and 50 and are in vertical axial alignment therewith to hold these rollers in contact with the faces 52 and 53 of the cam 51. The cam and the yoke will thus

cooperate to prevent swinging movement of the latch 32 and will hold the latch in locking engagement with the strike plate 29. A pivot pin 61 is carried by the yoke 58 and is disposed near the leg 59 which is on the side of the pivot 57 nearest to the door hinges or pivots. The pin 61 provides a pivotal connection for a latch bar 62 which extends horizontally within the channel 11'. A latch rod 63 is connected to the free end of the bar 62 by a pin 64. The rod 63 extends through a bearing 65 and has a reduced end portion 66 which extends through a bearing 67. A lug 68 extends outwardly from the side of the bearing 65 and has a bore 69 through it to receive a latch pin 70. The latch pin 70 carries a collar 71 through which the latch rod 63 extends. This collar has a central bore of greater diameter than that of the latch rod 63 which will permit the collar to shift laterally in a plane normal to the axis of the rod 63. A trip member 72 extends outwardly from the side of the rod 63, and when the collar 71 is shifted to an eccentric position with relation to the rod, the pin will prevent longitudinal movement of the rod 63 toward the latch structure. The pin 70 has an enlarged head 73 at its outer end which is urged outwardly by a spring 74. The spring is disposed between the head and the lug 68. Thus, when the door 14 is open the spring will urge the head 73 outwardly and will draw the collar 71 over to an obstructing position with relation to the lug 72 on the rod 63. When the door closes the head 73 will be encountered and will force the pin inwardly.

Fixed upon the latch rod 63 near its reduced end portion 66 is a laterally extending lug 75 formed with a bore 76 through it. This bore accommodates a guide rod 77 for a spring 78 and is fitted with a nut 79 to adjust the effective length of the rod. A trip bar 80 is slidably guided by the bearing 67 and has a turned end portion 81 formed with a bore 82 to receive the guide rod 77 and a bore 83 to receive the reduced end portion 66 of the latch rod. The spring 78 is interposed between the lug 75 and the turned portion 81. A spring 84 acting in the opposite direction is interposed between the turned portion 81 of the latch bar 80 and the bearing 67. The trip bar 80 slides horizontally within the lintel channel 11 as moved by rotation of a torque rod 85. The torque rod 85 is disposed vertically within a housing 85' which is secured to and forms a part of the door post 10 adjacent to which the door 14 is hinged. This rod at its upper end projects into channel 11 and carries a torque lever 86. At the free end of the torque lever is an upwardly projecting pin 87 which engages a face of an extension 88 formed on the end of the trip bar 80 opposite to the extension 81 and parallel therewith. The pin 87 is designed to engage the extension 88 and draw the trip bar 80 in the direction of the torque rod 85. As here shown and described the torque rod 85 is designed to transmit motion to the trip bar 80 through the swinging movement of lever 86.

The torque rod 85 is fitted with a trigger 89 which is disposed at substantially the level of the panic bolt cross-bar 21 and in the path of travel of the member 25. Thus when the panic bolt cross-bar 21 is forced inwardly toward the door the member 25 will encounter an inclined face 89' on the trigger 89 and will release the latch 40 as will be hereinafter set forth.

In order that the door may be retained in unlatched position a key lock structure generally

indicated at 90 is provided. This includes an outer housing 91 secured within the door post and mounted to extend through the outer leg 13 of the post channel. Mounted within the outer end of the housing is a lock barrel unit 92 which may be actuated by a key 93. Secured to the operating mechanism of the barrel unit is a threaded stem 94 which engages a nut 95. The thread on the stem 94 is a multiple thread of steep pitch so that the stem will be quick acting. The nut 95 is carried by a plunger 96 which reciprocates longitudinally of the housing 91. The end of the plunger opposite to the nut 95 is designed to engage a lever arm 97 which extends through a slotted opening in the side of the housing 91 and is here shown as a part of the trigger 89 which is fixed upon the torque rod 85. Thus, when the plunger 96 is moved to its extreme position within the housing 91 as indicated in Fig. 8 the torque rod 85 will be held in rotated latch releasing position.

In operation of the panic bolt structure with which the present invention is concerned, the latch control mechanism is assembled completely in the channel structure of the door frame which includes the channel door posts 10 and the lintel 11. This assembled structure is then in condition for surface application to the doorway at the time of installation and is a substitute for the usual door stops and frame structure. As previously stated, a pair of doors may be used or one door, as shown in the drawings. In any event the door is mounted upon the pivots 17 and 18 and is supported in a manner to give desired clearance so that the door will swing freely over the threshold. The roller strike plate 29 is properly adjusted with relation to the latch member 32 so that the latch will hold the door in its locked position, at which time the latch cam 51 will be in the position shown in Fig. 4 and the yoke 58 will be disposed with its legs 59 and 60 in obstructing positions beneath the rollers 49 and 50. At this time the door 14 will be closed and latched. If it is desired to retain the latch in released position the key 93 may be inserted in the keyhole of the lock barrel structure 92 so that the pin 94 may be rotated to force the plunger 96 against the lever arm 97 and thus swing the pin 87 against the extension 88 of the bar 80. A reverse operation will of course release the entire latch mechanism so that the door latch may be controlled by movement of the panic bolt cross-bar 21.

When it is desired to release the door latch by the panic bolt cross-bar 21 pressure is exerted against the bar to swing it in the direction of the arrow *a* in Fig. 6 of the drawing. This will cause the cam member 25 to swing inwardly and engage the inclined face 89' of the trigger 89. The trigger will then swing in the direction of the arrow *b* as shown in Fig. 6 of the drawing and will rotate the torque rod 85. This in turn will cause the lever arm 86 to rotate in the same direction so that the pin 87 on the end of the lever arm will engage the extension 88 of the trip bar 80 and will pull the latch rod 63 in the direction of the arrow *c*, as shown in Fig. 2. This pull will be against the expansion of spring 84. When the latch rod 63 is pulled in the direction of the arrow *c* the latch bar 62 will also be pulled, and this will act through the yoke 58 to swing the latch cam 51 in the direction of the arrow *a*, as indicated in Fig. 5 of the drawing. When this takes place the cam surface 53 of the member 51 will engage the roller 50

which is carried on extension arm 46 of the latch structure 32. The result will be that the arms 46 and 46 of the latch 32 will swing downwardly in the direction of the arrow *e*, as indicated in Fig. 3 of the drawing, and the latch 40 will swing upwardly to clear the strike roller 41. The latch 40 will thus swing free of the strike plate and the door will swing toward its open position by continued pressure upon the panic bolt cross-bar. At this same time the door will relieve its pressure upon the head 73 of the pin 74 and will thus shift the collar 71 laterally of the latch rod 63. Thus when pressure on the panic bolt cross-bar is relieved the action of springs 78 and 84 will tend to restore the latch rod 63, the latch bar 62 and the cam 51 to their original positions, as indicated in Fig. 4 of the drawings. The collar 71, however, will be engaged by the lug 72 on the rod 63 and will prevent this movement until the door is again closed. When the door is closed again it will engage the head 73 of the pin 70 and shift the collar 71 to a non-obstructing position. The spring 78 will then produce end thrust on the rod 63 and move the cam 51 to the position shown in Fig. 4, thus swinging the strike roller 42 downwardly and in locking position with relation to the strike plate. At the same time the arms 59 and 60 of the yoke 58 will move into an obstructing position beneath the rollers 49 and 50 and will hold the latch 32 in its locked position. The operation of restoring the latch parts to the positions shown in Fig. 4 of the drawings as previously described is aided by the force of the spring 40' which tends to swing the latch 40 downwardly toward an engaging position and also tends to lift the rollers 49 and 50 to the position shown in Fig. 4. The simultaneous lifting action of the rollers 49 and 50 will aid in restoring cam member 51 to the position shown in Fig. 4.

From the foregoing description it will be evident that the door will be positively latched when it is closed, and that it will be automatically and instantly opened when pressure is applied to the panic bolt cross-bar. Furthermore, it will be noted that manipulation of the latch structure by the panic cross-bar cannot take place except when the door is closed and when the door has engaged the head 73 of the pin 70 to move the collar 71 into a non-obstructing position with relation to the lug 72 on the latch bar 63.

It will thus be seen that the panic bolt lock structure here disclosed is of simple construction and provides parts which are strong and are not liable to break or get out of order, the structure being so designed as to be assembled compactly with the channel members of a door frame, thus making it possible for the entire lock structure to be assembled at the plant and installed as a unit at the point of application. It will also be noted that by the lock and latch structure here disclosed it is possible to positively lock the door to temporarily latch it in a manner to insure that when pressure is applied to the panic bolt this will transmit a movement to the latch structure which will automatically and naturally unlatch the door as pressure is applied against the door and the bolt in an effort to open the door as would be the situation under panic conditions.

While I have shown the preferred form of my invention as now known to me, it will be understood that various changes may be made in com-

bination, construction and arrangement of parts by those skilled in the art, without departing from the spirit of the invention as claimed.

Having thus described my invention, what I claim and desire to secure by Letters Patent is:

1. A latch structure of the panic bolt type to be used in combination with a door frame and a swinging door, comprising a latch carried by the door frame for engaging the edge of the swinging door adjacent to its free end, latch operating means extending longitudinally within the frame of the door and acting to positively latch the door when the door is closed, said latch operating means having a trigger, and a panic bolt cross-bar carried by the door and adapted to be moved to engage said trigger and actuate said latch operating means.

2. A latch structure of the panic bolt type to be used in combination with a door frame and a swinging door, comprising a latch carried by the door frame for engaging the edge of the swinging door adjacent to its free end, latch operating means extending longitudinally within the frame of the door and acting to positively latch the door when the door is closed, said latch operating means having a trigger, a panic bolt cross-bar carried by the door and adapted to be moved to engage said trigger and actuate said latch operating means, and means forming a part of said latch operating means and acting to hold the latch in a non-engaging position and responsive to the closing of said door to restore said latch to door-latching position.

3. A latch of the panic bolt type for use in combination with a door frame and a swinging door, comprising, a latch member pivotally mounted in the door frame and adapted to move to an engaging position with the door, positive means for moving the latch member toward and away from its latching position, said means including an operating structure incorporated within the lintel of the door frame and a torque rod extending vertically down the door post adjacent to the pivot of the door, a panic bolt cross-bar mounted upon the door and upon a horizontal axis, and cooperating means between said cross-bar and the torque rod for rotating the torque rod when the cross-bar is moved toward the door.

4. The structure of claim 3 including means acting to hold the latch structure in a non-latching position while the door is open and for releasing the latch structure when the door has been closed.

5. A latch of the panic bolt type for use in combination with a door frame and a swinging door formed with a recess in its upper edge, comprising an overhanging latch member pivoted on a horizontal axis within the lintel of the door frame and having a free end adapted to swing into the recess in the upper edge of the door, a pair of arms formed upon the opposite end of the latch member, each arm carrying a roller disposed on a horizontal axis, a cam disposed between said arms and mounted upon a horizontal pivot within the lintel of the door frame, said cam being formed with oppositely and downwardly inclined cam faces with which said rollers may be in simultaneous engagement, a lever extension formed as a part of said cam structure and being disposed below its pivotal axis, a draw-bar assembly connected with said lever and extending horizontally within the lintel, a vertically extending torque rod mounted for rotation within a housing provided on the post of the door adjacent to its pivotal edge,

means cooperating with the torque rod and the draw-bar assembly to actuate the latch member when the torque rod is rotated, a panic bolt cross-bar pivoted on a horizontal axis upon the door, and cooperating means between the cross-bar and the torque rod for rotating the torque rod when the cross-bar is moved inwardly.

6. A latch of the panic bolt type for use in combination with a door frame formed with a channel-shaped lintel and within which frame a door having a recess in its upper horizontal edge is mounted for swinging motion, comprising adjacent to its free vertical edge, a latch arm mounted within the lintel channel of the door frame for vertical swinging movement, the free end of said latch arm overhanging the recess in the edge of the door when the door is closed, a pair of horizontally spaced arms formed integral with the latch plate and extending oppositely from the pivotal axis of the plate, a pair of rollers, one mounted at the end of each of said arms and spaced from each other, a cam structure pivoted upon a horizontal axis at right angles to the axis of the latch and in a vertical plane intermediate the rollers, said cam structure having a portion extending downwardly in the space between the rollers and being formed with downwardly and inwardly inclined arcuate cam faces by which the rollers are engaged, whereby when the cam oscillates upon its pivot one of the rollers will be engaged to lift the latch from engagement with the strike plate, a latch bar pivotally connected to the lever portion of said cam and extending longitudinally of the channel-shaped lintel, a torque rod extending vertically and rotatably supported by the door post adjacent to the door pivot, a connection between the torque rod and said operating rod whereby as said rod rotates the operating rod will be drawn to swing the cam, a panic bolt cross-bar mounted upon a horizontal axis on the door, and a trigger carried by the torque rod and engaged by the cross-bar to cause the torque rod to rotate.

7. An overhead latch structure for a swinging door having a recess in its upper edge adjacent to its free end and a strike plate mounted within said recess comprising, a latch mounted within the lintel of the door frame, said latch comprising a latch arm extending horizontally from the lintel of the door frame and overhanging the swinging door, bearings mounted within the lintel of the door frame for supporting the latch arm for vertical swinging movement, means at the free end of said arm for engaging the strike plate, a pair of extension arms fixed to the latch arm and being disposed parallel to each other upon the opposite side of the pivotal axis of the arm, a pair of rollers, one carried on the free end of each of said arms, their axes being at right angles to the pivotal axis of the latch arm, a latch cam mounted within the lintel of the door and having opposite downwardly and inwardly inclined faces to be engaged by said rollers, a horizontal pivot for said cam in a plane below the plane of the axes of the rollers when the latch arm is in its latching position, a lever extension fixed with relation to the latch cam and extending below the pivotal axis thereof, a U-shaped yoke member pivoted to said lever extension and having up-turned legs adapted to move to obstructing positions beneath the rollers when the rollers are in their uppermost positions and the cam is in its normal centrally aligned position, whereby the latch arm will be held in

its latched position, a latch bar pivotally connected to said yoke adjacent to one leg thereof whereby a pull on said bar will impart a swinging movement to the latch cam and will move the legs of the yoke out of an obstructing position with relation to the rollers, and means for moving said latch bar.

8. The structure of claim 7 including an operating bar loosely connected to said latch bar, yieldable means interposed between the latch bar and the operating bar tending to separate said bars, yieldable means acting to resist movement of the operating bar in a direction to move the latch bar, and means for positively moving the operating bar in said direction.

9. The structure of claim 7 including a latch trip structure associated with said latch bar and adapted to hold the latch arm in its non-latching position when the door is open.

10. A latch structure of the panic bolt type to be used in combination with a door frame and a swinging door therein including; a latch mounted in the lintel of the door frame and adapted to engage the swinging door and hold it against swinging movement, a trigger mounted on the post of the door frame, a panic bolt cross-bar pivotally mounted upon the door for vertical swinging movement, said panic bolt cross-bar being adapted to engage the trigger and move the same, and operating means between the trigger and the latch whereby movement of the trigger will be transmitted to the latch to move the same.

11. A latch structure of the panic bolt type to be used in combination with a door frame and a swinging door therein including; a latch mounted in the lintel of the door frame and adapted to engage the swinging door and hold it against swinging movement, a trigger mounted on the post of the door frame, a panic bolt cross-bar pivotally mounted upon the door for vertical swinging movement, said panic bolt cross-bar being adapted to engage the trigger and move the same, operating means between the trigger and the latch whereby movement of the trigger will be transmitted to the latch to move the same, and yieldable means tending to move the latch toward its latching position.

12. In a latch structure of the panic bolt type for use with a swinging door mounted within a door frame having side posts and a top lintel, a panic bolt cross-bar mounted upon the door to swing vertically when pressure is exerted thereagainst, a latch trigger pivotally mounted on the post of the door frame and adapted to be engaged and moved by the end of the panic bolt cross-bar as it swings toward the door, and a door latch mechanism mounted in said lintel connected with and actuated by said trigger.

13. In a latch structure of the panic bolt type for use with a swinging door mounted within a door frame having side posts and a top lintel, a panic bolt cross-bar mounted upon the door to swing vertically when pressure is exerted thereagainst, a latch trigger pivotally mounted on the post of the door frame and adapted to be engaged and moved by the end of the panic bolt cross-bar as it swings toward the door, a door latch mechanism mounted in said lintel connected with and actuated by said trigger, and means forming a part of said latch mechanism and holding the same in a positively locked position until actuated by said trigger.

14. In a latch structure of the panic bolt type

75

for use with a swinging door mounted within a door frame having side posts and a top lintel, a panic bolt cross-bar mounted upon the door to swing vertically when pressure is exerted thereagainst, a latch trigger pivotally mounted on the post of the door frame and adapted to be engaged and moved by the end of the panic bolt cross-bar as it swings toward the door, door latch mechanism mounted in said lintel connected with and actuated by said trigger, means forming a part of said latch mechanism and holding the same in a positively locked position until actuated by said trigger, and means actuated when the door is in its open position to hold the latch means in its non-latching position.

15. The combination with a swinging door, a frame including side posts and a top lintel, a latch in the top lintel and a panic bar on said door, of a latch operating mechanism including a trigger mounted on one of said posts in the path of movement of said panic bar, and a linkage from said trigger extending upwardly therefrom to said lintel, said linkage including means extending along said lintel to said latch, whereby said latch may be operated by and with actuation of said trigger by said panic bar.

16. In a latch device for use with a swinging door mounted within a door frame having side posts and a top lintel, the combination of: a cross-bar mounted upon said door to move toward said door when pressure is exerted against said bar; a latch trigger mounted on a post of the door frame in a position to be engaged and moved by said cross-bar when the latter is pressed toward said door; a door latch mechanism provided on said door frame and holding said door closed; and means on said door frame operatively connecting said trigger with said latch mechanism to move the latter by said movement of said trigger to release said door.

17. In a latch device for use with a swinging door mounted within a door frame having side posts and a top lintel, the combination of: a cross-bar mounted upon said door to move toward said door when pressure is exerted against said bar; a latch trigger mounted on a post of the door frame in a position to be engaged and moved by said cross-bar when the latter is pressed toward said door; a door latch mechanism provided on said door frame and holding said door closed; means on said door frame operatively connecting said trigger with said latch mechanism to move the latter by said movement of said trigger to release the door; and housing means on said door frame for enclosing said latch means, said connecting means and the mounting for said latch trigger, said trigger extending through said housing and into the path of movement of said cross-bar when the latter is shifted toward said door.

DANIEL C. HAY.
